(57) **CLAIM**

The ornamental design for a refill for air freshener device, as shown and described.

DESCRIPTION

FIG. 1 is a perspective view of a first embodiment of a refill for air freshener device showing our new design.

FIG. 2 is a front view of the refill for air freshener device of FIG. 1.

FIG. 3 is a left side view of the refill for air freshener device of FIG. 1.

FIG. 4 is a right side view of the refill for air freshener device of FIG. 1.

FIG. 5 is a back view of the refill for air freshener device of FIG. 1.

FIG. 6 is a top view of the refill for air freshener device of FIG. 1.

FIG. 7 is a bottom view of the refill for air freshener device of FIG. 1.

FIG. 8 is a perspective view of a second embodiment of a refill for air freshener device.

FIG. 9 is a front view of the refill for air freshener device of FIG. 8.

FIG. 10 is a left side view of the refill for air freshener device of FIG. 8.

FIG. 11 is a right side view of the refill for air freshener device of FIG. 8.

FIG. 12 is a back view of the refill for air freshener device of FIG. 8.

FIG. 13 is a top view of the refill for air freshener device of FIG. 8; and,

FIG. 14 is a bottom view of the refill for air freshener device of FIG. 8.

The broken line showing of environmental structure in the figures is for illustrative purposes only and forms no part of the claimed design.
